EXTENSION LEAF TABLE

Peter Hansen, Fayetteville, N. Y., assignor of
one-half to Leopold Stickley, Fayetteville,
N. Y.

Application September 1, 1930. Serial No. 479,117

1. Claim. (Cl. 45—113)

This invention relates to certain new and useful improvements in extension leaf tables in which the leaves are normally stored beneath the table top and adapted to be moved into the plane 5 of the table top and into co-operative relation with the ends of said top whereby the length of the table may be increased.

The main object of this invention is to provide means for removably supporting the table 10 extension leaves in co-operative relation with the ends of the table top in a rigid and secure manner.

Other objects are to provide a construction for supporting the table extension leaves that is simple, durable and inexpensive and which may be 15 quickly and easily manipulated to bring the leaves into and out of co-operative relation with the table top.

Other objects and advantages relating to the 20 details of the structure and relation of the parts thereof, will more fully appear from the following description taken in connection with the accompanying drawings in which:

Figure 1 is a perspective view of a table embodying the various features of my invention, and 25 illustrates one of the extension leaves concealed beneath the table top and the other leaf in the raised position in co-operative relation with the adjacent end of the table top.

Figures 2 and 3 are enlarged detail transverse 30 sectional views taken respectively on lines 2—2 and 3—3, Figure 1.

Figure 4 is an enlarged detail longitudinal sectional view taken on line 4—4, Figure 5.

Figure 5 is a horizontal sectional view taken 35 in the plane of the line 5—5, Figure 4, illustrating the table support and the extension leaves' slide bars in top plan.

Figure 6 is an enlarged detail sectional view 40 taken on line 6—6, Figure 5, illustrating the manner in which the extension leaves are hingedly connected with the slide bars.

Figure 7 is a detail vertical section taken on line 45 7—7, Figure 6.

Figure 8 is a perspective view of one of the hinge members for supporting the extension leaves.

My invention, as illustrated in the drawings, 50 consists of a conventional table top —1— rectangular in plan view, and has secured to the underside and midway between the ends thereof, a pair of spacer strips —2— positioned one adjacent either vertical edge of the table top. The spacer strips —2— are relatively short compared with 55 the length of the table top —1— and may be se-

cured thereto by any suitable means as by screws —3—.

Beneath the table top —1— and between the spacer strips —2—, is positioned a slide bar supporting frame —4— which, in this instance, is composed of upper and lower supporting members —5— and —6— respectively, of substantially the same width as the length of the spacer strips —2— and which are maintained in uniform spaced relation by a plurality of, in this instance 60 six, guide members —7— which are secured to the supporting members —5— and —6— in any suitable manner as by screws —8—.

The guide members —7— are arranged in two sets composed of three members each, each set 65 being positioned adjacent respective ends of the supporting members —5— and —6—, the members of each set being arranged in parallel spaced relation to form suitable guide slots —9— for receiving respective slide bars —10— adapted to 70 support the extension leaves, as hereinafter more fully explained.

The slide bar supporting frame —4— is secured to the under side of the table top —1— midway 75 between the ends thereof by screws —11— passing through the upper supporting member —5— and screw-threaded into said table top. The table top —1— with the slide bar supporting frame —4— connected therewith, is supported upon a suitable frame —14— which, in this instance, is 80 like the table top —1— rectangular in plan view and slightly smaller in outline than said top.

The frame —14— consists of a pair of side members —15— which extend in parallel spaced relation longitudinally of the table top —1— and 85 a pair of end members —16— arranged to extend transversely of the table top and across the ends of the side members —15— to which said end members —16— are secured in any manner well-known to those skilled in the art.

The frame —14— may be supported by one or more legs, depending upon the desire of the manufacturer, but for clearness, I have shown four legs as —17— positioned one at each corner 90 of the frame in any suitable manner, not necessary herein to illustrate.

The table top —1— is mounted symmetrically 95 upon the frame —14— and maintained in spaced relation thereto by the spacer strips —2— which rest upon the side members —15— and to which the frame is secured in any suitable manner as by screws —18—, see Figure 2. The spacer strips —2—, as hereinbefore mentioned, are relatively 100 short in length compared with the length of the 110

table top —1— which leaves a space or opening —20— adjacent either end of said strips and between the table top —1— and the frame —14—, and each of these openings or slots —20— are utilized to receive a table extension leaf as —21— when said leaves are not in use.

Each of the extension leaves —21— is of less thickness than the width of the opening —20— so as to permit the free movement of the leaves 10 into and out of the respective openings. The length of each leaf is substantially equal to the width of the table top —1— and the width of each leaf is made substantially equal to the distance between the spacer strips —2— and the 15 adjacent ends of the table top —1— so that when the leaves are positioned beneath the table top, the outer edges of the leaves will be in the vertical plane of the adjacent edges of the table top so that the table will present a neat and finished appearance when the leaves are in the concealed position beneath the table top.

Each of the leaves —21— is hingedly secured 20 to a pair of slide bars —10— hereinbefore mentioned, and which are mounted for longitudinal reciprocal movement beneath the table top —1— in the slide bar supporting frame —2—, each slide bar being positioned in a respective guide slot —9— of the slide supporting frame —4—, as shown more clearly in Figures 2, 4 and 5.

30 The slide bars —10— are arranged in two pairs, the inner positioned bars constituting one pair, while the outer positioned bars are connected together to form the other pair.

35 The bars comprising the inner positioned pair of slide bars, are connected at their outer ends by a transversely disposed bar —24— which has the ends thereof positioned in a suitable opening provided in the ends of the slide bars and connected therewith by pins —25— or other suitable means. The outer positioned pair of slide bars are likewise connected by a similar cross bar —26— connected with the ends of the respective bars —10— by pins —27— similar to the pins —25— for the other pair of bars.

45 Each of the slide bars —10— is provided with a pair of cavities —29— formed in longitudinal spaced relation adjacent the outer end thereof. Each of the bars —10— is also provided with a 50 relatively narrow elongated slot —30— at each cavity —29— and preferably adjacent the outer wall thereof, and which extends below the cavity and beyond either end thereof for pivotally receiving a hinge member —31—.

55 The hinge —31— in this instance, has the upper strap —31'— thereof substantially rectangular in plan view and is secured by screws —32— to the undersurface of an extension leaf —21—. The other strap as —31'— of the hinge member —31— is formed angular in cross section with 60 one leg as —33— thereof hingedly connected with the other strap member —31'— constituting the hinge, while the other leg —34— of the strap —31'— extends below the leg member —33— and is provided with an opening —35— there-through for receiving a pin —36— for pivotally connecting the hinge member to the respective slide bar —10— in the following novel manner: The leg —34— of each hinge —31— is positioned in the slot —30— with the hole —35— thereof in registration with a similar hole —37— provided transversely of the bar —10— beneath each of the cavities —29— as shown more clearly in Figures 6 and 7. The other or shorter leg member —33— is positioned in the respective cavity —29— in such a manner that when the leaf

—21— carried by said hinge is in the raised position, the leg member —33— will contact with the outer end —29'— of the respective cavity —29— for limiting the outward movement of said hinge and leaf, and when said leaf is moved to the lowered position in contact with the upper face of the supporting slide bars —10—, said hinge will register in the respective cavity —29—.

80 It will therefore be seen that each leaf is provided with four hinges —31— connecting said leaf with the respective pair of slide bars —10— and that when the leaf is in the raised position, it will be securely maintained therein against outward movement by the hinges contacting with the outer wall of respective cavities —29—.

85 The slide bars —10— are of such a length that when the bars are moved outwardly to bring the leaf carried thereby into co-operative relation with the adjacent end of the table top —1—, the inner ends of said bars will be in registration with the slide bar supporting frame —4—, as illustrated more clearly in Figure 5, while the outer ends of the bars are supported by the adjacent end member —16— of the frame —14— and which are provided with suitable slots or recesses —40— or —40'— in the upper edge thereof, for receiving the slide bars therethrough, said slots being of such a depth as to engage the undersurface of the respective slide bars —10— to 90 form a rigid support for the outer ends of the slide bars, and also for the table leaves when said leaves are in the operative position in contact with the respective ends of the table top —1—.

95 In operation, considering that the table leaves are in the concealed position beneath the table top —1—, it is only necessary for the operator to grasp the tie bars —24— and —26— and draw the leaves and respective supporting slide bars, outwardly a sufficient distance to bring the extension leaf connected therewith beyond the outer end of the table top —1—. Then, by rocking the leaf —21— upwardly about the axis of the pivotal pins —36— until the strap —31'— of the hinge —31— engages the outer ends —29'— of the respective cavities —29—, the leaf —21— will be brought into the plane of the table top —1—. Then, all that is necessary to bring the leaf into co-operative relation with the table top, is to move the slide bars —10— together with the leaf —21— carried thereby, inwardly until the inner edge of the leaf engages the outer adjacent end of the table top —1—.

100 It is now evident that the table leaves —21— will be maintained in a rigid and secure manner in co-operative relation with the table top —1— due to the fact that the supporting hinges —31— are prevented from rocking outwardly about the pivotal supports —36— by the end walls of the cavities —29—, while the leaves are prevented from moving inwardly due to their engaging relation with the table top —1— and that the leaves are maintained against downward movement by the rigid support which the end members —16— and the slide bar supporting frame —4— provides for the slide bars —10—.

105 Although I have shown and described the preferred embodiment of my invention, I do not wish to be limited to the exact form and relation of the parts thereof, as various changes may readily be made without departing from the spirit of this invention, as set forth in the appended claim.

110 I claim:
115 In an extension table, the combination with a

supporting frame, of a table top fixedly secured to said frame to extend over the entire upper surface thereof, an extension leaf normally positioned beneath the table top, slide bars supported for longitudinal movement by the table top and by said frame each bar being provided with longitudinally spaced cavities and an elongated slot at each cavity of greater depth than said cavity, and hinge members connecting the leaf with said bars whereby the leaf may be moved into the plane of the table top when said bars are in the extended position, each of said members including a hinge strap secured to the leaf and a second strap comprising a pair of legs of unequal length arranged at right angles to each other, the shorter of said legs being positioned in the cavity and the longer leg extended into the slot and a pin pivotally securing the longer leg to the slide so that when the shelf is raised to the operative position in the plane of the table top, the shorter leg will abut against one end of the cavity for limiting the outward swinging movement of the hinge strap and maintaining the leaf in the plane of the table top, and when the leaf is in the inoperative position beneath the table top, the entire hinge will lie within the cavity below the upper face of the slide.

PETER HANSEN.
